No. 12,291

May 31, 1881

UNITED STATES PATENT OFFICE.

AUGUST WILL, OF JERSEY CITY, NEW JERSEY, ASSIGNOR TO DAVID WOLFE BRUCE, OF NEW YORK, N. Y.

DESIGN FOR A FONT OF PRINTING-TYPE.

SPECIFICATION forming part of Design No. 12,291, dated May 31, 1881.

Application filed April 6, 1881. Term of patent 14 years.

To all whom it may concern:

Be it known that I, AUGUST WILL, (assignor to DAVID WOLFE BRUCE,) of Jersey City, Hudson county, New Jersey, have invented and produced a new and Original Design 5 for a Font of Printing-Type, of which the following is a specification.

The nature of my design is clearly shown in the accompanying typographic impression, to 10 which reference is made; and it consists of a design for a font of printing-type intended for the formation of borders and ornamental surroundings for printed matter.

The motive of the design is Assyrian, and I 15 will describe the various members of which the font is composed.

No. 1 to No. 14 represent signs, symbols, or letters in use among the Assyrians.

No. 15 is a figure composed of two wedge-shaped figures, the upper boundaries of which are curved and united together. At the point of joining a dot is found.

No. 16. Upon the left is a light line joined at its upper termination by a heavy horizontal 25 line.

No. 17 is the reverse of No. 16.

No. 18 is a short heavy horizontal line.

No. 19 is a short light horizontal line.

No. 20 is a short light inclined line.

No. 21 is a representation of a pine-apple.

No. 22 is a fret composed of the heavy figure placed within a light figure following the configurations of the inner figure.

No. 23 is a capital of the Ionic order of architecture.

No. 24 is a section of the entablature of an Assyrian temple.

No. 25 is a figure composed of a heavy waving figure above a second heavy waving figure.

No. 26 is an architectural ornament consisting of the molding formed of two parallel lines, between which are placed the heavy dots, above which is placed the heavy line, centrally triangulated below and surmounted by a line gradually widening into the heavy triangular termination. Upon each side are placed the inclined lines, gradually widening into the heavy triangular terminations.

No. 27 is a section of molding composed of the heavy figure with concaved sides; above and below the figure is continued by the light

curved lines. Upon each side of the figure, about centrally, are placed the short curved lines.

No. 28 is a section of a molding composed of the heavy oblong figures, these concaved, one upon the left, the other upon the right, one having the inclined sides upon the right, the other upon the left, the space between these figures shaded by the pointed or inclined light 60 lines succeeded by heavy ones, and the figures ornamented above and below by the light curved lines continued from the heavy figures. Upon each side of the heavy figures are placed the curved lines.

No. 29 is a section of a compound molding, the base composed of two horizontal lines, one above the other, followed by a heavy horizontal line, succeeded by a series of light horizontal lines; above a heavy horizontal line 70 surmounted by a light horizontal line.

No. 30 is an architectural ornament consisting of a scroll-like figure shaded upon its face at intervals by the short heavy vertical lines, upon each side of which are the light vertical 75 lines; this scroll-like figure adorned about centrally by a rhomboidal-like ornament, upon each side of which are placed the short curved-line figures shaded upon the face by the light curved lines, these shaded below by the heavy 80 curved lines.

No. 31 is a representation of a tassel.

No. 32 is a feather-like figure used as an architectural ornament.

No. 33 is a representation of a palm-leaf.

No. 34 is a figure composed of a series of light loop-like ornaments gradually rising to form a semicircle shaded upon its face by a series of heavy curved lines placed above each other. The loop-like figures proceed from a 90 light curved line forming the base of the figure.

Nos. 35 and 37 are lotus-like figures.

No. 36 is an architectural ornament, the upper portion or outer boundary formed by the 95 inuated-like line, the face shaded by the indented-like line, below which is placed the heavy indented-like line shaded by a light indented-like line; below this the base of the figure, composed of a short heavy horizontal line 100 between two short light horizontal lines.

No. 38 is the center of the figure, two con-

centric rings, the inner one a heavy one, the outer a light one. Above are placed the leaf and flower like ornaments; below, extended to the right and to the left, the figures composed of 5 curved lines ornamented upon the face by a series of small heavy dots placed at intervals. From the center depend the short curved lines upon the right and left of a figure composed of two inclined lines with a vertical central 10 line.

No. 39 is a corner-piece for a border, composed of two vertical lines, met at the upper termination by two horizontal lines, the spaces between the lines ornamented by a series of 15 small heavy dots placed at intervals, the figure crossed at its upper left-hand corner by a series of heavy-shaded plume-like ornaments extending above and below.

No. 40 is a circular tile, the heavy outer 20 line of which is shaded by a lighter line following its configuration, ornamented upon its face by a sixteen-pointed star-like figure, in the center of which is placed an unshaded ring, this star-shaped figure resting upon a many-pointed circular figure, shaded as shown.

No. 41 is an architectural ornament resembling a fleur-de-lis, below which is placed a heavy-line molding followed by a central vertical line gradually widened to form a triangular-like base, upon each side of which are placed the heavy curved lines with central triangular-like ornaments.

No. 42 is a circular tile, the outer boundary of which is the heavy circle shaded by a light 35 one, ornamented centrally by the heavy ring surrounded by a series of rays shaded upon the face by the short heavy lines, this followed by an outer circular figure formed with indentations, as shown.

No. 43. Upon the right of the figure is a 40 small ring followed by a larger one, ornamented upon its face by a central ring surrounded by the rays, as shown, from which larger ring proceed the tassels, as shown.

No. 44 is an architectural ornament, the center ornamented by a pine-apple rising from a 45 heavy husk-like ornament. On each side of the pine-apple are placed the heavy plume-like ornaments. Upon each side of the pine-apple, at its base, extend the figures composed of slightly-curved horizontal lines ornamented 50 upon the face at intervals by the small heavy dots. Similar figures are also found upon each side of the plume-like ornaments intertwining 55 around the base of the same.

No. 45 is an architectural ornament consisting of the feather-like ornaments proceeding from a central elliptical ring, ornamented upon its face by a short heavy horizontal line. 60 Below the elliptical ring is the border composed of the horizontal lines curving at the inner ends. The space between is ornamented at intervals by the small heavy dots. Below this, centrally, is placed the looped-like figure, upon 65 each side of which is the heavy curved figure,

gradually widening to its outer termination and shaded by a light line following its outer boundary.

No. 46 is an architectural ornament, the upper portion of which is composed of the three 70 pine-apples grouped together, the stems of which are united at about the center of a semi-elliptical curved figure, the space between the curved terminations of which is filled by the heavy pointed figure, as shown. Below, centrally, is placed the heavy bud-like figure with the leaves upon each side, from which project outward, below the base of the curve upon each side, the curved leaf-like ornaments. 75

No. 47 is an architectural ornament, consisting of a group of feathers rising from a vase below a molding ornamented upon its face by the short heavy inclined lines meeting to form a point. Upon each side of the group of feathers is placed a representation of a sacred 80 ram.

Nos. 48 and 49 are representations of kings of Assyria. In No. 48 the king is represented as holding in one hand an open-work ornament; in No. 49 as holding a mace. 85

No. 50 is a representation of a winged horse. 90

No. 51 is a representation of the sphinx.

Nos. 52 and 53 are bas-reliefs representing 95 Assyrian warriors.

No. 54 is a representation of a winged bull.

No. 55 is a representation of a Pegasus.

No. 56 is a representation of a winged human-headed bull. 100

No. 57 is the reverse of No. 56.

Nos. 58 and 59 are bas-reliefs—lions in a crouching position. 105

Nos. 60 and 61. No. 60 is a bas-relief representing a horse decorated and attendant. No. 61 is a bas-relief representing a horse and 110 attendant armed with a rod.

Nos. 62 and 63 represent bas-reliefs from palace of Nimroud. In No. 62 the figure is represented as bearing a kid, and in one hand a lotus and acorns. In No. 63 the king is represented bearing a sword. 115

Nos. 64 and 65 are representations of Assyrian divinities, Astarte being represented in No. 65.

Nos. 66 and 67 represent bas-reliefs from 115 the palace of Nimroud. No. 66 is a vulture-headed figure armed with a staff or mace. No. 67 is a second vulture-headed figure holding in one hand a fir cone, in the other a basket.

Nos. 68 and 69 are bas-reliefs representing 120 winged human-headed bulls.

Having now described my invention, what I claim as new is—

The design for a font of printing-type, as shown as described.

AUGUST WILL.

In presence of—

WILLIAM V. H. HICKS,
A. SIDNEY DOANE.
